AERATOR

Filed Nov. 10, 1928

Inventor
John B. Fletcher

By

E. W. Bradford

Attorney

UNITED STATES PATENT OFFICE

JOHN B. FLETCHER, OF NEW YORK, N. Y., ASSIGNOR OF ONE-HALF TO JOHN L. McGUCKEN, OF TAMPA, FLORIDA.

AERATOR

Application filed November 10, 1928. Serial No. 318,400.

My invention relates to an aerator designed primarily for supplying or charging water with air, but which is susceptible of other uses.

5 It is an object of the invention to provide a device of this character which will force the water upwardly in a fine spray thereby breaking it up sufficiently to permit the escape of obnoxious gases which tend to make 10 the water stale, and at the same time permitting the water to become charged with oxygen.

It is also an object of the invention to provide a simple inexpensive machine economical of operation and one which will cause 15 only a very slight evaporation of the water; all as will be hereinafter more particularly specified and claimed.

20 Referring to the accompanying drawings, which are made a part hereof and on which similar reference characters indicate similar parts,

Figure 1 is a vertical section illustrating one application of my invention, and

25 Figure 2, a section on line 2—2 of Fig. 1.

In the drawings reference character 10 indicates the base of the device which in the present instance is formed of cast metal or the like but which may be constructed of 30 other desired material. The base has underlying strengthening fins or webs 11, said base being provided with supporting feet 12. A plurality of legs 13 of angle iron or similar metal are secured in spaced relation 35 upon the base 10 and converge toward their upper ends and have such ends secured to a disc 14 which forms a support for a motor 15, such motor being of a construction which is not injured by its being exposed to water.

40 The motor 15 is provided with a depending shaft 16 connected by means of a universal joint 25 with a shaft 16' which extends down into close proximity to the base 10 and rests upon a ball bearing 17 in a socket 18 in a supporting cup 19. The shaft 16 has an impeller 20 of ordinary three-blade construction mounted on its lower portion in spaced relation from the base of the device, adapted 45 to be rotated for forcing the water in a spray upwardly.

A plurality of baffle plates 21 are disposed radially about the motor shaft in order to prevent rotation of the water below the impeller, and said baffle plates rest on edge and are cut out at their inner upper corners to 55 accommodate the impeller, but have their lower portion extending beneath the blades of the impeller in close proximity to the motor shaft. The upper edges of the baffle plates terminate in a plane slightly above 60 the plane of the impeller and thus when the impeller is rotating, water may pass in toward the impeller radially, such water being prevented from rotating by the baffle plates is sprayed upwardly and outwardly 65 in a graceful curve, being at the same time finely divided to permit the escape of obnoxious gases such as for example sulphur gas and the like, and at the same time permitting the absorption of oxygen from the atmosphere. 70

With some aerators there is a very great loss by evaporation which amounts in some cases to as high as fifteen per cent. With my device the evaporation is scarcely perceptible being never more than three and one-half per cent. 75

It will be obvious to those skilled in the art that various changes may be made in my device without departing from the spirit of the invention, and I, therefore, do not limit myself to what is shown in the drawings and described in the specification, but only as set forth in the appended claims. 80

Having thus fully described my said invention, what I claim as new and desire to secure by Letters Patent, is:

1. An aerator comprising a support, an impeller mounted to rotate in a horizontal plane above the support, and baffle plates arranged vertically in radial relation around the impeller and extending beneath the same in close proximity to its axis, substantially as set forth. 90

2. An aerator comprising a support, an impeller, and baffle plates disposed on edge around said impeller and extending beneath the same in close proximity to its axis, substantially as set forth. 95

3. A device for aerating water comprising 100

a base, a top, legs connecting said base and top, driving means associated with the top, a shaft operated by the driving means and depending through the top and resting upon the base, an impeller on said shaft adjacent its lower end, and baffle plates mounted on said base in edgewise position and extending beneath said impeller in close proximity to said shaft, substantially as set forth.

10 4. A device for aerating water comprising a base, a top, legs connecting said base and top, driving means associated with the top, a shaft operated by the driving means and depending through the top and resting upon the base, an impeller on said shaft adjacent its lower end, and baffle plates mounted on said base in edgewise position and extending beneath said impeller in close proximity to said shaft, said baffle plates having their 15 upper edges extending above the impeller and being cut out to accommodate the impeller, substantially as set forth.

In witness whereof, I have hereunto set my hand at Washington, District of Columbia, this fifth day of November, A. D. nineteen hundred and twenty-eight.

JOHN B. FLETCHER.
